UNITED STATES PATENT OFFICE.

CHARLES B. BELKNAP, OF DETROIT, MICHIGAN.

DISHWASHING APPARATUS.

Application filed November 6, 1920. Serial No. 422,136.

To all whom it may concern:

Be it known that I, CHARLES B. BELKNAP, a citizen of the United States, residing in the city of Detroit, county of Wayne, and 5 State of Michigan, have invented certain new and useful Improvements in Dishwashing Apparatus, of which the following is a specification.

This invention is an improvement on a 10 similar invention filed as an application April 16, 1919, in the name of Jane T. Belknap, the latter being issued as Letters Patent No. 1,345,059, June 29th, 1920.

This invention relates to improvements in 15 dish washing apparatus and has among its salient objects to provide a construction in which the dishes or utensils being washed are simultaneously bodily reciprocated and rotated in a cleansing fluid; to provide a construction in which the utensils being washed are placed in a rack or cage detachably mounted on a constantly reciprocating and 20 rotating spindle or shaft, whereby sufficient agitation of the cleansing fluid is obtained to thoroughly clean said utensils, and to provide a construction which is devoid of parts 25 difficult to clean or complicated in operation and one in which the water for cleansing or rinsing may be maintained at any desired 30 temperature.

The important feature of this invention is the particular type of driving shaft used in connection with this dish washing apparatus.

35 In the drawings—

Figure 1 is a vertical side elevation, partly in section, of the improved device.

Fig. 2 is a plan view of the rack or cage.

Fig. 3 is a detail view of the reciprocating 40 mechanism.

Referring to the drawings—1 designates a suitable frame on which is mounted a water-tight tank 2 provided with a cover 3. The tank, which is preferably of cylindrical 45 shape, is provided with a centrally disposed vertical extending sleeve 4 having watertight bearings 5 and 6. In these bearings is rotatably mounted a shaft or spindle 7, the upper end of which projects through the 50 bearing 6 and is squared to receive the hub 9 of the dish rack 10. Handles 10^a are fitted on the edge of the rack to facilitate its removal from the tank 2. This rack 10 is provided with a plurality of removable baskets 55 11 mounted one above the other, the baskets being divided, as shown, to receive plates,

cups, glasses, silverware and the like. It is, of course, apparent that, as the shaft is rotated and reciprocated simultaneously, the rack or cage 10 will revolve within the tank 60 and be raised and lowered with the reciprocation of the sleeve 4.

Describing now the manner of actuating the shaft 7—this shaft is in two parts joined by a tongue and groove connection as shown 65 at 13, the lower end mounted in a lower bearing 12 the upper section of the shaft having a bifurcated lower end 14 fitting over the vertical tongue 15 of the lower section 7^a. Through the upper section of the shaft 7 70 extends a transverse pin 16 having rotatable ends which are adapted to roll in a slotted passage or groove 18 cut in a sleeve 19, the latter being fixedly mounted upon a bracket 20 riveted or bolted to the frame 1 of the 75 apparatus. Screw plugs 20^a are fitted in holes in the sleeve and furnish a means for removing the pin 16 from the vertical shaft. On the lower end of the shaft is fixedly 80 mounted a worm gear 21 meshing with a similar gear 22 mounted upon the shaft 23 to which power is supplied from any suitable source (not shown). The rotation of the shaft 23 being transmitted to the vertical shaft by the worm gears, gives a rotary motion to the rack containing the utensils to be cleaned. The reciprocatory movement is produced by the travel of the transverse pin 16 in the cam slot or groove 18 cut in the sleeve 19. 90

The tank 2 is filled with hot water and cleaning fluid, which may be heated by a burner 24 to any desired temperature. Suitable suds, of course, can be obtained by the use of soap or like substances. 95

As the shaft 7 is reciprocated and rotated, sufficient agitation of the water will be obtained to thoroughly and uniformly clean the utensils in the rack. After the dishes or utensils have been washed, the soapy water is drawn off through a valve 25 and the utensils cleaned with rinsing water, which may also be drawn off through the same valve. By this manner of washing and rinsing the dishes, I am able to subject them to sufficient heat to thoroughly sterilize them, which cannot be accomplished where the dishes are washed by hand, as the complete sterilization of the dishes is not possible unless the water is at substantially boiling point. 100 105 110

It is understood that the invention is not

limited in any way to the particular mechanism of reciprocating and rotating the shaft except as defined in the appended claims.

I claim as my invention:

- 5 1. In a machine for washing dishes, the combination with a tank for holding a cleansing liquid mounted on a frame, of a vertical two part shaft carrying a rack adapted to hold utensils to be cleaned rotating in the tank, power means axially rotating the shaft, and roller bearings on the upper section of the two part shaft operating in a cam slot, causing vertical recipro-

cation of the rack within the tank with the axial rotation.

2. In a machine for washing dishes, the combination with a tank for holding a cleansing liquid, of a utensil rack in the tank mounted on a vertical two part shaft, power means adapted to axially rotate the shaft, and roller bearings set transversely of the upper section of the two part shaft tracking in a cam slot in a fixed sleeve and adapted to produce a vertical reciprocation of the rack with the axial rotation of the shaft.

CHARLES B. BELKNAP.
